BOBBIN WINDER FOR SEWING MACHINES

John D. Karle, Roselle Park, N. J., assignor to
The Singer Manufacturing Company, Elizabeth, N. J., a corporation of New Jersey

Application November 20, 1937, Serial No. 175,601

13 Claims. (Cl. 242—22)

This invention relates to bobbin-winders for sewing machines and it has among its objects to provide an improved device of this nature which will have a straight line movement between its operative and inoperative positions; which will afford a more convenient adjustment to compensate for wear in the usual rubber-tired drive-wheel; which will provide a greater leverage on the latch-lever that holds the device in operative position, whereby the lever may be shifted by less pressure on the thread; and which will eliminate the usual upstanding portion of the motor-supporting casting on which, in prior constructions, the spindle-carrying arm was pivotally mounted. In the prior constructions this upstanding portion was in the way of the operator's thumb and interfered with the manual turning of the balance-wheel.

With the above and other objects in view, as will hereinafter appear, the invention comprises the devices, combinations and arrangements of parts hereinafter described in connection with the accompanying drawings in which—

Fig. 1 is a plan view, partly in section, of one end of a sewing machine bracket-arm embodying a preferred form of the present improved bobbin-winder.

Fig. 2 is an end view of Fig. 1, looking in the direction indicated by the arrow A, but with the hand-wheel and parts carried thereby omitted.

Fig. 3 is a sectional view substantially on the lines 3—3 of Figs. 1 and 4.

Fig. 4 is a vertical sectional view substantially on the line 4—4 of Fig. 3.

Fig. 5 is a vertical sectional view substantially on the line 5—5 of Fig. 1.

Fig. 6 is a detail rear end view of a portion of the bobbin-winder, looking in the direction indicated by the arrow B in Fig. 3.

Fig. 7 is a perspective view of a latch-lever forming a part of the improved bobbin-winder.

Fig. 8 is a view similar to the upper portion of Fig. 3 but showing the bobbin-winder in its inoperative position.

Fig. 9 is a diagrammatic view illustrating a camming action on the bobbin-winder latch-lever, later to be described.

Fig. 10 is a view similar to Fig. 5 but showing a modified construction.

Referring more specifically to the drawings, the invention is disclosed as embodied in a sewing machine, comprising a frame 1 formed with a cylindrical bearing-boss 1^a in which is journaled a main or needle-bar driving shaft 2. At its rear end the shaft 2 has secured thereto, as

by a pin 3, a sleeve 4 upon which is rotatably journaled a hand- or balance-wheel 5, provided with an annular rim or runway 6. As shown in the drawings, the wheel 5 is adapted to be rotated by an electric motor M through the medium of a worm 7 secured upon the motor shaft 8 and a cooperating worm-wheel 9 fixed to the hub 5^a of the balance-wheel 5. It is to be understood, however, that any other suitable means may be employed to rotate the balance-wheel. Clutch means, comprising a manually rotatable clamp-screw 10, threaded into the sleeve 4, as shown most clearly in Fig. 4, is provided for clamping the balance-wheel to the sleeve 4 so that rotation of the balance-wheel will drive the main shaft 2. The hub 5^a of the balance-wheel is journaled on the sleeve 4 between an annular shoulder 4^a thereon and a thrust washer 11 slidingly mounted on the outer end of the sleeve. The clamp-screw is adapted to bear against the washer 11 and thereby clamp the hub of the balance-wheel between the washer and the shoulder 4^a to cause the sleeve 4 and main shaft 2 to be rotated by the balance-wheel. The rim 6 of the balance-wheel serves to actuate the bobbin-winder, later to be described, and, to permit bobbins to be wound without rotating the main shaft, the clamp-screw 10 may be backed off to unclamp the balance-wheel from the sleeve 4. Pins 11^a, carried by the washer 11, cooperate with the inner end of a stop-screw 13 threaded into the clamp-screw 10 to prevent undue loosening of the clamp-screw.

The mechanism hereinbefore described is substantially the same in construction and operation as that forming the subject of United States patent to W. J. Peets, No. 1,934,373, Nov. 7, 1933. Also as disclosed in the Peets patent, the motor M and its shaft 8 are carried by a bracket or casting 12 secured to the frame 1, as by screws 14. After assembly, the bracket 12 is, in effect, a portion of the frame 1 and for the purpose of this disclosure may be so considered.

The Peets patent discloses a conventional form of bobbin-winder including an upwardly and forwardly inclined arm 51 on which is pivoted the bell-crank lever 53 which carries the bobbin-winder spindle 54. As hereinbefore stated, these upstanding parts are somewhat in the way of the operator's thumb and interfere with the manual turning of the balance-wheel. The Peets patent also embodies a latch-lever 57 to hold the bobbin-winder in operative position during the winding of the bobbin and which is tripped to throw the bobbin-winder out of action when the bobbin is 55

filled. This latch-lever has a relatively short actuating lever-arm and therefore a considerable pressure on the thread is required to trip the latch. In some cases this excessive pressure on the thread is undesirable.

The present improved bobbin-winder eliminates the upstanding portions which were in the way of the operator's thumb; it substitutes a straight line movement for the swinging movement of the spindle carrier; it provides increased leverage for the latch-lever whereby it may be tripped by less pressure on the thread, and it provides a convenient adjustment to compensate for wear in the rubber-tired drive wheel.

The preferred form of bobbin-winder, as disclosed in Figs. 1 to 9, comprises a supporting rod 15, of uniform diameter throughout, translatable but nonrotatably mounted within a horizontally disposed cylindrical bore 16 formed in a tubular bearing boss 17 perpendicular to the main shaft 2. This boss may be provided by the frame 1 or it may be formed integral with the motor-supporting casting 12. At its forward end the rod 15 has a transverse head 18 formed with a bore 19 in which is rotatably journaled a spindle 20 adapted, at one end, to receive and hold a sewing machine bobbin B. At its opposite end the spindle 20 has secured to it a rubber-tired driving wheel 21, adapted, in the inner position of the rod 15, to engage the annular rim 6 of the balance-wheel, whereby rotation is transmitted from the balance-wheel to the spindle 20 and the bobbin carried thereby. To prevent the rod 15 from rotating in its bearing, the rear end of the rod carries a horizontally disposed plate 22 which projects laterally from the rod and slides in transverse slots 23 formed in the side walls of the bearing boss 17. The wall at the inner end of this slot forms an abutment for the plate 22 and thereby limits the outward movement of the rod 15.

Latch means is provided for holding the rod 15 in its innermost, or bobbin-winding position, with the wheel 21 in driving contact with the rim 6 of the balance-wheel. This latch means comprises a lever 24 fulcrumed intermediate its ends on a shoulder screw 25 threaded into the bearing boss 17. The forward end of the lever 24 is curved, as shown at 24^a, and is adapted to bear upon the thread being wound upon the bobbin. A coiled spring 26, located within a cavity 27 in the bearing boss 17, about the screw 25, has one off-set end 26^a secured in the bearing boss and the other off-set end 26^b engaging the latch-lever 24, and normally urges the forward end of the lever downwardly into contact with the thread on the bobbin. The rearward end 24^b of the lever 24 forms an abutment for a block 28 adjustably secured, by a screw 29, to the transverse plate 22, carried by the supporting rod 15, and serves, during a bobbin-winding operation to hold the rod in its innermost position thereby to maintain the rubber-tired wheel in contact with the rim 6 of the balance-wheel. The block 28 serves as means to adjust the rod 15 axially to compensate for wear in the wheel 21 and also to predetermine the amount of thread to be wound on the bobbin. The rod 15 and the parts carried thereby are normally urged outwardly, to the position indicated in dotted lines in Fig. 5, in which the wheel 21 is out of contact with the rim 6 of the balance-wheel, by a coil-spring 30 having one end located within a bore 31 formed in the bearing boss 17 parallel with the bore 16. The outer end of the spring bears against the

transverse head 18 of the rod 15. A sheet-metal sleeve 32 surrounds and protects the spring 30 and has one end fixed within a bore 33 in the head 18. The other end of the sleeve is slidably mounted in the bore 31.

The lever 24 preferably is made of a sheet-metal stamping and is bent intermediate its ends along a line x-x, Fig. 7, so that its forward portion lies substantially in a horizontal plane while its rearward portion stands in a vertical plane, as shown most clearly in Figs. 1 and 7. As illustrated in Fig. 9, the rearward end 24^b of the latch-lever 24 is formed as an arc of a circle the radius R of which extends from the fulcrum-point of the lever. Therefore swinging of the latch-lever 15 under the influence of the thread on the bobbin will have no effect on the supporting rod 15 until the upper corner of the latch-lever is moved below the lower edge of the plate 28.

Fig. 10 illustrates a modification which differs from the construction shown in Fig. 5 in that, in the modified construction, the translatable rod 15^a, having a transverse head 18^a which carries the spindle 20, is made of two diameters and is fitted within a stepped bearing. The smaller diameter 15^b is slidably mounted in a bore 16^a in the bearing boss 17 and the larger diameter 15^c is fitted within a counterbore 16^b in the boss. In place of the spring 30 (Fig. 5) for shifting the rod, and the parts carried thereby, the modified construction employs a larger spring 30^a located within the counterbore 16^b between a shoulder 15^d on the rod and the bottom wall 16^c of the counterbore.

The operation of the improved bobbin-winder is as follows. The operator, having released the clamp-screw 10 to disconnect the balance-wheel from the main shaft, places an empty bobbin B' on the free end of the spindle 20 and manually winds the thread T a few turns thereon. Next she pushes inwardly on the head 18 to force the rubber-tired wheel 21, from the position shown in Fig. 8, into driving contact with the rim 6 of the balance-wheel. This movement causes the block 28 to ride off the end of the tail 24^b of the latch-lever 24, whereupon the spring 26 turns the latch-lever clockwise and places the tail 24^b thereof in the path of movement of the block, as shown in Fig. 3, and prevents endwise movement of the rod 15 under the influence of the spring 30. Rotation of the balance-wheel by the motor M will then rotate the spindle 20 and cause the thread to be wound on the bobbin. The curved portion 24^a of the latch-lever bears upon the thread on the bobbin and, as the thread builds up thereon, it gradually shifts the lever 24 counter-clockwise until, when the bobbin is filled, the tail 24^b releases the block 28 and permits the spring 30 to shift the rod 15 and the parts carried thereby to the inoperative position shown in Fig. 8. As illustrated diagrammatically in Fig. 9, the angle of the upper edge 24^c of the tail-piece 24^b to the bottom surface 28^a of the block 28 is such that as the block is shifted forward by the spring 30 it has a camming action on the latch-lever and thereby tips it slightly counterclockwise as viewed in Fig. 9, and raises the forward end 24^a out of contact with the thread and above the side wall of the bobbin to facilitate removal of the bobbin from the spindle. This camming action also serves as a shock-absorber, or snubber, on the rod 15 and thereby eases it into its inoperative position.

Having thus set forth the nature of the invention, what I claim herein is:

1. A bobbin-winder, for sewing machines hav-

ing a frame and a balance-wheel supported by said frame and provided with an annular runway, comprising an endwise movable supporting rod slidably mounted in said frame, a rotatable 5 bobbin-carrying spindle carried by one end of said supporting rod, a drive-wheel secured to said spindle and adapted to be engaged with the annular runway on said balance-wheel, spring means normally acting to shift said rod endwise to position 10 said drive-wheel out of contact with said runway, a latch-lever fulcrumed intermediate its ends on a stationary portion of the sewing machine, one end of said lever being adapted to bear upon the thread being wound on the bobbin and the 15 other end forming an abutment, and a member secured to the other end of said rod and cooperating with said abutment to maintain said supporting rod in a position to hold said drive-wheel in contact with said runway until said lever is 20 shifted sufficiently by the thread to move said abutment out of the path of said member.

2. A bobbin-winder, for sewing machines having a frame and a balance-wheel supported by said frame and provided with an annular runway, comprising an endwise movable supporting rod slidably mounted in said frame, a head on one end of said rod, a bobbin-carrying spindle journaled in said head transverse to said supporting rod, a drive-wheel secured to said spindle 25 and adapted to be engaged with the annular runway on said balance-wheel, spring means normally acting to shift said rod endwise to position said drive-wheel out of contact with said runway, a latch-lever fulcrumed intermediate its 30 ends on a stationary portion of the sewing machine, and a member secured to the other end of said rod and cooperating with said latch-lever to maintain said supporting rod in a position to hold said drive-wheel in contact with said runway.

3. A bobbin-winder, for sewing machines having a frame and a balance-wheel provided with an annular runway, comprising a bearing boss formed on said frame and provided with a bore and a transverse slot, an endwise movable supporting rod slidably mounted in the bore in said bearing boss, a head on the forward end of said rod, a bobbin-carrying spindle journaled in said head transverse to said supporting rod, a plate secured to the rearward end of said rod and 40 having projecting ends slidably fitted within the slot in said bearing boss to prevent rotation of said rod, a drive-wheel secured to said spindle and adapted to be engaged with the annular runway on said balance-wheel, spring means normally 45 acting to shift said rod endwise to position said drive-wheel out of contact with said runway, a latch-lever fulcrumed intermediate its ends on a stationary portion of the sewing machine, and a member secured to the rearward end of said rod and 50 cooperating with said latch-lever to maintain said supporting rod in a position to hold said drive-wheel in contact with said runway.

4. A bobbin-winder, for sewing machines having a frame and a balance-wheel provided with an 55 annular runway, comprising an endwise movable supporting rod slidably mounted in a bore in said frame, a rotatable bobbin-carrying spindle carried by one end of said supporting rod, a drive-wheel secured to said spindle and adapted to be 60 engaged with the annular runway on said balance-wheel, spring means normally acting to shift said rod endwise to position said drive-wheel out of contact with said runway, a latch-lever fulcrumed intermediate its ends on a stationary portion of the sewing machine, and a 65

member adjustably supported by the other end of said rod and cooperating with said latch-lever to maintain said supporting rod in a position to hold said drive-wheel in contact with said runway.

5. A bobbin-winder, for sewing machines having a frame provided with a bearing boss formed with a bore and a transverse slot and a balance-wheel provided with an annular runway, comprising an endwise movable supporting rod slidably mounted in said bore, a bobbin-carrying spindle rotatably journaled at one end of said supporting rod, a plate secured to the other end of said rod and slidably fitted within the transverse slot in the frame to prevent rotation of said rod, a resilient drive-wheel secured to said spindle and adapted to be engaged with the annular runway on said balance-wheel, spring means normally acting to shift said rod endwise to position said drive-wheel out of contact with said runway, a 10 latch-lever fulcrumed intermediate its ends on a stationary portion of the sewing machine, and a member adjustably secured to said plate and cooperating with said latch-lever to maintain said supporting rod in a position to hold said drive-wheel in contact with said runway, the adjustment of said member serving to compensate for wear on said drive-wheel.

6. A bobbin-winder as set forth in claim 1, in which the latch-lever is made of a sheet metal 30 stamping bent intermediate its ends to afford a horizontally disposed portion adapted to bear on the thread being wound on the bobbin and a vertically disposed portion adapted to receive a fulcrum-screw and to provide said abutment.

7. A bobbin-winder as set forth in claim 1 in which that end of the latch-lever which affords the abutment is formed as an arc of a circle, the axis of which coincides with the axis of the fulcrum of the latch-lever, whereby movement 40 of the latch-lever under the influence of the thread being wound on the bobbin has no effect on the spindle-supporting rod until the end of the latch-lever is moved below the path of movement of said cooperating member.

8. A bobbin-winder as set forth in claim 1 in which the upper edge of the abutment end of the latch-lever is arranged at an acute angle to, but in the path of movement of, the cooperating member carried by the supporting rod, whereby movement of said member, when the bobbin-winder 50 is shifted to inoperative position, causes the latch-lever to be tipped about its fulcrum to lift the forward end thereof out of contact with the thread on the bobbin, the latch-lever also serving as a shock-absorber for the supporting rod.

9. A bobbin-winder as set forth in claim 2 in which the means for shifting the supporting rod axially comprises a coil-spring interposed between the frame and the transverse spindle-supporting head at one side of and parallel to said rod.

10. A bobbin-winder as set forth in claim 3 in which the bore in the bearing boss and the supporting rod movable therein are each formed 65 of two diameters and the means for shifting the rod axially comprises a coil-spring located in the larger bore and surrounding the smaller diameter of the rod.

11. The combination with a sewing machine 70 frame, a rotary shaft journaled therein and a balance-wheel coaxial with said shaft and adapted to be connected therewith, said balance-wheel being provided with an annular runway, of a bobbin-winder comprising a rod slidable endwise 75

- in said frame at right angles to said shaft, a bobbin-supporting spindle carried by said rod, a spindle-driving wheel secured to said spindle and adapted to engage said runway, a spring normally acting to shift said rod in one direction to disengage said driving wheel from said runway, latch means for holding said driving wheel in engagement with said runway in opposition to said spring, and means actuated by the thread wound on the bobbin to release said latch means.
12. In a sewing machine, in combination, a frame, a motor-supporting bracket secured thereto, a rotary shaft journaled in said frame, a balance-wheel coaxial with said shaft and adapted to be connected therewith, said balance-wheel being provided with an annular runway, an electric motor carried by said bracket and adapted to rotate said balance-wheel, and a bobbin-winder comprising a supporting rod slideable endwise in a bore in said bracket at right angles to said shaft, means to prevent rotation of said rod in said bore, a bobbin-supporting spindle carried by said rod, a spindle-driving wheel secured to said spindle and adapted to engage said runway, a spring normally acting to shift said rod in one direction to disengage said driving wheel from said runway, latch means for holding said driving wheel in engagement

with said runway in opposition to said spring, and means actuated by the thread wound on the bobbin to release said latch means.

13. In a sewing machine, in combination, a frame, a motor-supporting bracket secured thereto and having at its upper portion a bearing-boss provided with a horizontally disposed bore, a rotary shaft journaled in said frame, a balance-wheel coaxial with said shaft and adapted to be connected therewith, said balance-wheel being provided with an annular runway, an electric motor carried by said bracket and adapted to rotate said balance-wheel, and a bobbin-winder carried by said bracket and comprising a rod slideable endwise in said bore perpendicular to said shaft, means to prevent rotation of said rod in said bore, a bobbin-supporting spindle carried by said rod, a spindle-driving wheel secured to said spindle and adapted to engage said runway, a spring normally acting to shift said rod in one direction to disengage said driving wheel from said runway, latch means for holding said driving wheel in engagement with said runway in opposition to said spring, and means actuated by the thread wound on the bobbin to release said latch means.

JOHN D. KARLE.
